UNITED STATES PATENT OFFICE.

FREDERICK WILL AND HUGO BECKER, OF ROCHESTER, NEW YORK, ASSIGNORS TO
SILL STOVE WORKS, OF ROCHESTER, NEW YORK, A CORPORATION OF NEW YORK.

DESIGN FOR A TOP FOR COAL-RANGES.

43,075.

Specification for Design.

Patented Sept. 24, 1912.

Application filed May 16, 1912. Serial No. 697,804. Term of patent 14 years.

To all whom it may concern:

Be it known that we, FREDERICK WILL and HUGO BECKER, citizens of the United States, residing at Rochester, in the county of Monroe and State of New York, have invented a new, original, and ornamental Design for Tops for Coal-Ranges, of which the following is a specification, reference being had to the accompanying drawing, forming a part thereof.

The figure is a perspective of a stove, showing our new design.

We claim:

The ornamental design for a top for coal ranges, as shown.

FREDERICK WILL.
HUGO BECKER.

Witnesses:

RUSSELL B. GRIFFITH,
H. E. STONEBRAKER.
